TRAVELING CONTACTING DEVICE

Edwin W. Wismar, Oakland, Calif., assignor to
Justin M. Jacobs, Hillsborough, Calif.

Application August 4, 1945, Serial No. 608,933

5 Claims. (Cl. 191—59)

1

This invention relates generally to traveling contacting devices suitable for use with trolley wires.

In Benbow Patent 2,255,874 there is disclosed a traveling contacting device making use of a chain-like endless series of conductor elements adapted to make continuous electrical connection with a trolley wire. In practice the conductor elements are carried by a trolley box or like body which also carries one or more bus bars disposed in spaced parallel relationship with the trolley wire. The conductor elements are arranged to pass between the bus bar and the trolley wire to thereby make continuous electrical connection.

The device as disclosed in said Patent 2,255,874 makes use of at least one and preferably two sheaves or wheels upon which the endless conductor chain is tracked. In another form of the device disclosed in Benbow co-pending application Serial No. 575,300, filed January 30, 1945, now Patent No. 2,501,203 dated March 21, 1950, the endless conductor chain is tracked upon sprocket wheels in place of sheaves.

It is an object of the present invention to provide a simplified type of traveling contacting device utilizing the invention of Benbow 2,255,874 but making possible elimination of sheaves or sprockets for tracking the endless conductor chain. A further object of the invention is therefore to provide a simplified traveling contacting device which can be manufactured at relatively low cost and which will be capable of long useful life with a minimum amount of servicing and repair.

Additional objects of the invention will appear from the following description in which the preferred embodiment has been set forth in detail in conjunction with the accompanying drawing.

Referring to the drawing:

Figure 1 is a side elevational view partly in section illustrating a device incorporating the present invention.

Figure 2 is a cross sectional view taken along the line 2—2 of Figure 1.

The apparatus as illustrated in the drawing consists generally of a traveling contacting device 10 which is adapted to operate in conjunction with a trolley wire assembly 11. A trolley assembly in this instance consists of a trolley wire or conductor 12 surrounded by a protective sheath 13 of insulating material, such as natural or synthetic rubber. The back side (upper side as illustrated) of this sheath is retained by the substantially T-shaped metal backing or mounting strip 14. The lower side of the sheath, or

2

what is normally the lower side when the contacting device 10 is operated in a vertical position, is provided with a series of recesses 16, separated by the teethlike bars 17 of insulating material formed integral with the remainder of the sheath. Recesses 16 permit electrical contact with the trolley wire 12 as will be presently explained. A suitable length of the assembly 11 is supported at intervals by the brackets 18.

The trolley contacting device 10 consists of a body 20 which is preferably formed of suitable molded insulating material, and split into two parts 20a and 20b. Carried by this body there is an endless series 21 of articulated conductor elements or what can be termed an endless conductor chain. Each of elements 22 making up this chain consists of an outer toothlike portion 22a, the end face of which can be notched or grooved as indicated at 22b to facilitate seating 20 upon the wire 12. The enlarged base portion 22c of each element is provided with slots or recesses 23.

The means for connecting adjacent elements 22 preferably consists of links 24 which have their 25 ends pivotally connected to elements 22 by the pivot pins 25. The end portions of links 24 are accommodated within the slots 23.

The body 20 also carries bus bar means for making continuous electrical contact with the elements 22. The bus bar means in this instance consists of a relatively rigid bar 27 made of suitable material such as hard copper or bronze. The end portions 28 of this bar are looped or bent back upon themselves to form curved guide portions for tracking the conductor chain 21, as will be presently explained. Preferably the curved portions 28 extend through arcs substantially in excess of 90°. In the detail illustrated they extend through arcs in excess of 180°.

In order to retain the bus bar 27 in normal operating position, while at the same time permitting limited movement of the same, the body is provided with studs or bolts 29, which are surrounded by the spacer sleeves 31. The sleeves 31 in turn carry the resilient rubber buffer sleeves 32. The proportioning of the sleeves 32 is such that these members are loosely embraced by the curved portions 28 of the bus bar, whereby the bus bar is permitted limited longitudinal movement and limited lateral movement in a direction toward the trolley wire 12.

As will be seen in Figure 1 the conductor elements are adapted to pass between the linear portion of the bus bar 27 and the trolley wire 55 12, with the tooth shaped portions 22a accommo-

dated within the recesses 16. Suitable spring means are provided for urging the bus bar toward the trolley wire, thus securing proper pressure for good electrical contact between the bus bar and the conductor elements 22, and between these elements and the trolley wire. The spring means shown in this instance consists of a pair of leaf springs 30 retained upon the body studs 33, and having their ends pressing at spaced points upon the linear portion of the bus bar 27 as illustrated. 10

Assuming that the device is operated in a vertical position as shown in Figures 1 and 2, it is desirable, but not essential, to support the lower run of the chainlike conductor. For this purpose the body can be provided with a pair of parallel ribs 34 between which the tooth shaped portions 22a may pass, but which serve as supporting sheaves for engaging the base portions 22a. Thus the lower run of the conductor chain is supported to minimize pressure and friction upon the curved portions 28.

In order to insure proper tracking of the device upon the trolley wire assembly the body is provided with two pairs of upstanding strips 36, the upper ends of which carry the tracking wheels 37. These wheels operate upon the shoulders 38 of the metal backing strip 14.

Suitable means can be provided to make connection between the bus bar 27 and an external conductor 39. Thus a terminal box 41 is formed on the body and is provided with an inner terminal block 42 with which cable 39 makes electrical connection. Bus strip 43 serves to connect this box with flexible feed conductors 44, which in turn are connected to the terminals of the bus bar 27.

Operation of the device described above can be explained as follows: When the device is traversed longitudinally of the trolley wire, as by means of a tow connection to a traveling crane carriage, the conductor chain progresses about the bus bar 27 with the teeth portions entering the cavities 16 to make electrical contact with the trolley wire 12. The bus bar is permitted limited movement relative to the body and is urged by springs 30 in a direction to maintain good electrical contact with the conductor elements. The conductor elements move freely about the curved end portions 28 without undue friction, and without necessitating the use of sheaves or sprockets such as utilized in prior practice. Freedom of movement about the curved portions 28 is enhanced by the support afforded by the ribs 34.

I claim:

1. In a traveling contacting device for a trolley wire comprising a body, a conducting bus bar carried by the body and adapted to move parallel to and in spaced relationship to the wire, end portions of said bus bar being looped to provide guide portions, and an endless chainlike series of articulated conductor elements mounted for movement between the bus bar and the wire to provide a conducting path therebetween, said elements being loosely guided about the end portions of the bus bar, portions of the said body forming an enclosed housing about the conductor elements and the bus bar.

2. In a traveling contacting device for a trolley wire comprising a body, a conducting bus bar carried by the body and adapted to move parallel to and in spaced relationship to the wire, looped portions formed on the ends of the bus bar, an end-

less chainlike series of articulated conductor elements disposed for movement between the bus bar and the wire to provide a conducting path therebetween, said conductor elements being loosely guided over the end portions of the bus bar, and spring means serving to urge the bus bar relative to the body and toward the wire.

3. In a traveling contacting device for a trolley wire comprising a body, an extended bus bar carried by the body and adapted to move parallel to and in spaced relationship to the wire, the ends of the bus bar being looped through arcs in excess of 90°, retaining members mounted upon the body and disposed within said looped end portions of the bus bar, thereby generally retaining the same against longitudinal movement, spring means serving to urge the bus bar toward said wire, and a chain like endless series of articulated conductor elements mounted for movement between the bus bar and the wire and loosely engaging about the looped portions of the bus bar, said elements serving to provide a conducting path between the wire and the bus bar.

4. In a traveling contacting device for a trolley wire comprising a body, a bus bar carried by the body and adapted to move parallel to and in spaced relationship to the wire, the ends of the bus bar being bent to form arcuate guide portions, retaining studs mounted upon the body and disposed within said arcuate guide portions, said studs being in proximity with the inner surfaces of the guide portions to thereby generally retain the bus bar against longitudinal movement while permitting lateral movement toward or away from the wire, spring means disposed generally between said studs and serving to urge the bus bar toward said wire, and a chainlike endless series of articulated conductor elements mounted for movement between the bus bar and the wire and loosely engaging about the arcuate guide portions, said elements serving to provide a conducting path between the wire and the bus bar.

5. In a traveling contacting device for a trolley wire comprising a body, a conducting bus bar with curved ends carried by the body adapted to move parallel to and in spaced relationship to the wire, retaining members mounted upon the body and disposed within the curved ends of the bus bar, said retaining members being disposed in proximity with the inner surfaces of said curved ends and permitting movement of the bus bar toward the wire and generally retaining the same against longitudinal movement, spring means to urge the bus bar toward the wire, and an endless series of articulated conductor elements mounted for movement between the bus bar and the wire to provide a conducting path therebetween, said elements being loosely guided over the curved ends of the bus bar.

EDWIN W. WISMER.
